UNITED STATES PATENT OFFICE

95,167

DESIGN FOR AN UPHOLSTERY FABRIC

Hans Wilde, Cliffside Park, N. J.

Application January 24, 1935, Serial No. 55,030

Term of patent 3½ years

To all whom it may concern:

Be it known that I, Hans Wilde, a citizen of the United States, residing at Cliffside Park, county of Bergen, State of New Jersey, have invented a new, original, and ornamental Design for Upholstery Fabric, of which the following is a specification, reference being had to the accompanying drawing, forming a part hereof.

The figure is a plan view of my new design for upholstery fabric. The dot and dash lines outline the design unit, which unit is repeated at regular intervals as indicated by the extensions beyond the unit boundaries.

I claim:

The ornamental design for upholstery fabric as shown and described.

In testimony wherof I have signed this specification.

HANS WILDE.
